DESIGN FOR A FAN PROPELLER

Bob Debenport, Fort Worth, Tex.

Application November 3, 1944, Serial No. 116,131

Term of patent 14 years

(Cl. D26—7)

To all whom it may concern:

Be it known that I, Bob Debenport, a citizen of the United States, residing at Fort Worth, in the county of Tarrant and State of Texas, have invented a new, original, and ornamental Design for Fan Propellers, of which the following is a specification, reference being had to the accompanying drawing, forming part thereof.

Figure 1 is a front elevational view of a fan propeller showing my new design; and Figure 2 is a side elevational view thereof.

I claim:

The ornamental design for a fan propeller, as shown.

BOB DEBENPORT.
